UNITED STATES PATENT OFFICE.

DANIEL J. BONCHER AND WILL E. DRAEB, OF KEWAUNEE, WISCONSIN.

FILE-CASE HANDLING DEVICE.

1,258,309.

Specification of Letters Patent.

Patented Mar. 5, 1918.

Application filed May 19, 1917. Serial No. 169,744.

To all whom it may concern:

Be it known that we, DANIEL J. BONCHER and WILL E. DRAEB, citizens of the United States, residing at Kewaunee, in the county 5 of Kewaunee and State of Wisconsin, have invented certain new and useful Improvements in File-Case Handling Devices, of which the following is a specification.

This invention relates to implements for 10 removing or depositing articles upon shelves which are located higher than can be conveniently reached by a person standing upon the floor, and has for one of its objects to simplify and improve the construction 15 and increase the efficiency and utility of a device of this character.

Another object of the invention is to provide an implement of this character which may be readily applied without material 20 structural change to engage articles of various sizes and forms.

With these and other objects in view, the invention consists in certain novel features of construction, as hereinafter shown and 25 described and then specifically pointed out in the claim; and in the drawings illustrative of the preferred embodiment of the invention.

Figure 1 is a side elevation of the im- 30 proved implement applied.

Fig. 2 is a perspective view of the handle or stock portion of the implement.

Fig. 3 is a detached perspective view of the holding portion of the device.

Corresponding and like parts are referred 35 to in the following description and indicated in all the views of the drawings by the same reference characters.

The improved implement may be adapted 40 without material structural change to handling various forms and sizes of objects, such as cartons or boxes containing goods of various kinds, but is more particularly adapted for use in handling file cases in 45 which papers are deposited, and to readily remove such articles from elevated shelves or other supports, and comprises a stock or handle 10 of any suitable size and of any suitable length, the length of the stock de- 50 pending upon the height of the shelf or other support upon which the article to be handled is located. The stock is preferably of wood with a metal ferrule 11 at one end and with a rod 12 extending from the ferruled end of 55 the stock, the rod being bent laterally to

form a hook-like terminal, as represented at 13. Spaced from the ferruled end of the stock is a bracket device comprising a body portion 14 extending obliquely to the longitudinal axis of the stock and extending toward the stock at its lower end as shown at 60 15, and secured to the stock at its ends, as represented at 16.

Connected to the obliquely directed portion 14 of the bracket is a holding member 65 formed from a single strip of metal bent substantially into U shape whereby side portions 17 are produced extending in parallel relation and with a seat 18 bent into the connecting portion of the holding member. 70 The seat is designed to receive the oblique portion 14 of the bracket to which it is rigidly secured by clamp screws 19 or like devices. The ends of the recess 18 bear against the side edges of the portion 14 of the 75 bracket, so that the side portions 17 are held from displacement relative to the bracket. The object to be handled, for instance a file case of conventional construction, is provided with an eye 20 near its upper edge 80 through which the hooked terminal 13 of the rod 12 is inserted, while the side portions 17 of the holding device engage the opposite sides of the article to be handled. The back members of file cases are usually of 85 wood, as indicated at 21, and the eye 20 is preferably in the form of an ordinary screw eye which is inserted into the wood back of the file case. Assuming that one or more of the file cases are deposited upon a shelf or 90 other support which is located at a higher point than could be conveniently reached by a person on the floor, the hook portion 13 of the rod 12 is inserted through the screw eye 20 and the sides 17 of the holding member 95 engaged over the opposite sides of the article. The stock 10 is then elevated to release the article from the shelf and draw it outwardly and lower it to the floor, the member 12—13 holding the article in position 100 while the side portions 17 of the holding member prevent lateral displacement. The article may be restored to the shelf by reversing the operation, as will be obvious.

The improved implement is simple in construction, can be inexpensively manufactured of any suitable material with the stock 10 of any suitable length to correspond to the height of the shelves on which the article to be handled is deposited.

Having thus described the invention, what is claimed as new is—

An implement of the class described comprising a stock having a reduced projection 5 at one end formed with a lateral offset and adapted to be engaged with the article to be moved, a bracket device attached to the structure and spaced from the reduced projection and including a body portion directed obliquely to the longitudinal axis of 10

the stock, and a supporting device connected to the obliquely directed portion of said bracket and including spaced sides adapted to engage the opposite faces of the article to be moved and maintain the same in an 15 inclined position.

In testimony whereof we affix our signatures.

DANIEL J. BONCHER. [L.S.]
WILL E. DRAEB. [L.S.]
